APPARATUS FOR FINISHING UPHOLSTERING

Filed Feb. 12, 1921

HORACE T. THOMAS INVENTOR.

BY

Raymond A. Parker
ATTORNEY.

UNITED STATES PATENT OFFICE.

HORACE T. THOMAS, OF LANSING, MICHIGAN.

APPARATUS FOR FINISHING UPHOLSTERING.

Application filed February 12, 1921. Serial No. 444,366.

To all whom it may concern:

Be it known that I, HORACE T. THOMAS, citizen of the United States, residing at Lansing, county of Ingham, State of Michigan, have invented a certain new and useful Improvement in Apparatus for Finishing Upholstering, and declare the following to be a full, clear, and exact description of the same, such as will enable others skilled in the art to which it pertains to make and use the same, reference being had to the accompanying drawings, which form a part of this specification.

My invention relates to a process and apparatus for finishing upholstery and a special object of my improvements is to provide for securing the ends of the finishing strips in automobile seats. In the accompanying drawings,

Figure 1 is a cross section of a top of a seat illustrating my invention.

Fig. 2 is a front elevation of the same.

Fig. 3 is a section substantially on the plane III—III of Fig. 1.

Fig. 4 is a section on the line IV—IV of Fig. 2.

Fig. 5 is a section similar to Fig. 4 illustrating the method of securing the finishing ferrule and end of the finishing strip.

Fig. 6 is a plan view of the ferrule, looking upon the top thereof to an enlarged scale.

Fig. 7 is an inverted plan view of the ferrule shown in Fig. 6.

a indicates the seat back. *a²* is the wooden cross piece or rail at the top of the seat. *b* is the finishing strip which is secured along the top of the seat-back over the top edge of the covering material. *c* indicates a securing nail passing through the strip *b* near its end and into the rail *a²*.

d is a finishing tip, or ferrule, for the end of the finishing strip *b*. This ferrule is made of sheet metal and is formed with a ridge *d²* concave within and concave outwardly extending transversely across the top of the ferrule near its inner end. The outer end of the ferrule is closed by the wall *d³*. *d⁴* *d⁴* are wings formed by bend-

ing inward the lower side edges of the ferrule. These wings do not come together for the greater part of their length but are extended somewhat at their rear ends as indicated at *d⁵* so that at this point the edges come approximately together. This forms shoulders *d⁶*, the utility of which will be hereinafter pointed out.

The manipulation of the above described apparatus is as follows:

The finishing strip *b* is first secured in position and the nail *c* at its end driven vertically through said strip into the rail *a²* and nearly home. The ferrule is then placed over the end of the finishing strip and the wings *d⁴* *d⁴* bent towards each other as shown in Fig. 5. A die *e* having its end provided with a matrix *e²* fitting over and shaped to the tip *d* is then placed over said tip and driven home with the blow of a hammer on its outer end, thus the wings *d⁴* *d⁴* are closely clasped under the end of the strip *b* between said strip and the rail *a²*, and the nail *c* which is within the ferrule *d* is at the same time driven snugly home, the die embracing the ferrule and holding it closely against the strip preventing any possible splitting of the strip. The ridge *d²* serves to strengthen the ferrule and the soft wood of the finishing strip extends somewhat up into the cavity of the ridge *d²* thus preventing the withdrawal of the ferrule from the strip. The nail *c* passes between the edges of the wings *d⁴* *d⁴* and the wood of the finishing strip *b* also engages the shoulders *d⁶*. The ferrule *d* can not be removed from the construction because the shoulders *d⁶* will engage the nail *c* and prevent such withdrawal.

Claims:

1. The combination of a finishing strip, a ferrule embracing the end of said strip, said ferrule being provided with a transverse ridge having a concavity within said ferrule for the purpose described. 90

2. The combination of a finishing strip, a ferrule placed over the end of said strip, said ferrule having inwardly bent edges extending under said strip for the purpose 95

described, said edges being shaped to form the shoulder d^6 .

3. The combination of a finishing strip, a ferrule placed over the end of said strip, said ferrule having inwardly bent edges extending over said strip for the purpose described, said edges being shaped to form

the shoulder d^6 and a nail passing through said strip in position to be engaged by said shoulder for the purpose described. 10

In testimony whereof, I sign this specification.

HORACE T. THOMAS.
